UNITED STATES PATENT OFFICE

GEORGE FRANKLYN MATTESON, OF ROCKY HILL, CONNECTICUT, ASSIGNOR TO THE FULLER BRUSH COMPANY, OF HARTFORD, CONNECTICUT, A CORPORATION OF CONNECTICUT

FEEDING MECHANISM FOR PUNCH PRESSES

Application filed May 2, 1925. Serial No. 27,573.

My invention relates to mechanisms for supplying pieces of material and for moving them to different positions for various operations thereon by different devices comprised 5 in the structure of a punch press or similar machine, and an object of my invention, among others, is the provision of means for utilizing the movements of the press to a maximum extent by effecting a number of 10 different operations successively upon a plurality of blanks at each reciprocating movement of the press head, whereby a series of different operations are progressively performed upon each blank in its travel to different positions with respect to said head.

One form of mechanism embodying my invention, and in the construction and use of which the objects herein set out, as well as others, may be attained, is illustrated in 20 the accompanying drawings, in which—

Figure 1 is a view in front elevation of a portion of the frame supporting my improved feeding mechanism, some of the smaller parts being omitted, for clearness 25 of illustration.

Figure 2 is a view, on an enlarged scale, illustrating the strip feeding and the ejecting mechanism.

Figure 3 is a top view of the feeding, transmitting and ejecting mechanism, the side part of the frame being cut in horizontal section.

Figure 4 is a detail view, scale still further enlarged, on a plane in vertical section denoted by the dotted line 4—4 of Figure 3, the punch plate being in its lowered position.

Figure 5 is a view similar to Figure 4 but showing the punch plate in its raised position, Figures 4 and 5 being shown on Sheet II.

Figure 6 (Sheet IV) is a view in vertical section on a plane denoted by the dotted line 6—6 of Figure 3.

Figure 7 (Sheet III) is a view, scale enlarged, in vertical section partially on a

plane denoted by the dotted line 6—6 of Figure 3, the punch plate being shown in its raised position.

Figure 8 is a view similar to Figure 7, but showing the punch plate in its lowered position.

In the accompanying drawings the numeral 10 denotes one of the side parts of a machine embodying my improved blank feeding mechanism, 11 a cross head connecting the side parts, 12 an operating shaft for the punch head and 13 the punch head operatively connected with the shaft 12 and guided by the side parts 10 in a manner that will be readily understood, the shaft 12 being connected with the driving mechanism of the machine as by means of pitmen 9 in a well known manner.

The strip feeding mechanism comprises means for projecting the end of a strip that extends, as from a roll supported on a stand or otherwise into position to be acted upon and also to be cut off, the blank comprising the cut off portion then being further acted upon by the mechanism, this strip feeding mechanism comprising a strip feed slide-block 14 mounted for reciprocating movement on a slide arm 15 secured to and projecting from the side part 10, and as shown in Figure 2 of the drawing. An anvil 16 on the slide block receives the strip 17 that is extended between said anvil and a gripper 18 in the form of a lever pivotally mounted on the block 14 and having a gripping jaw 19 to grip the strip in a manner that will be readily understood, the gripper being connected by a link 20 with a grip operating lever 21 pivotally attached to a supporting arm 22 secured to and extending from the side part 10 of the frame, and as shown in Figure 1. The lever 21 is actuated by a cam 23 secured to a cam shaft 24 through the medium of a connecting rod 25, said cam shaft forming a part of the driving mechanism of the machine, but the driving connection therefore

being omitted herein as not essential to a clear understanding of the invention.

Blank ejecting mechanism comprises a sliding bar 26 mounted for longitudinal reciprocating movement in a groove 27 in the arm 15, said bar having an ejecting pusher 28 secured to and projecting from its end through an opening 29 in the side part 10 of the frame, this pusher being of inverted trough shape to fit upon a forming die to be hereinafter described. This bar 26 is operatively connected to the lever 21 for operation thereby and as shown in dotted lines in Figure 2 of the drawing. A strip retaining pawl 30, in the form of a bell crank lever, is pivotally supported on a bracket within the opening 29, one arm of said lever resting in contact with the strip 17 and the other arm of said lever bearing a weight 31 that acts to hold the opposite end of the lever engaged with the strip that is pressed into contact with a spring seated detent jaw 33 (the spring not being shown herein) located in a socket in a bracket 32 that is secured to the side part 10 and that supports the pawl 30, the end of the lever or pawl opposite the gripping end bearing the weight 31. That portion of the side part 10 supporting the bracket 32 is cut away in Figure 2 of the drawings.

The end of the strip 17 is pushed by the mechanism just described into an opening formed between a housing 34 and a die block 35 supported on a bed 36 of the machine, said housing being secured to the die block in any suitable manner, as by means of screws, and being recessed to form an opening for the reception of the end of the strip, and as shown in Figure 4 of the drawing. A strip positioner 37 is located in a recess in the die block 35 and is spring pressed into contact with the end of the strip 17 as it passes into the housing 34, and as shown in Figures 4 and 5 of the drawings. A hole is formed in the housing through which a cutting punch 38 secured to a punch plate 39 passes in the operation of cutting off the end of the strip 17 to form a blank 40, a cutting die 41 secured in a recess in the die block 35 acting in cooperation with the cutting punch to sever the end of the strip 17, and as shown in Figures 4 and 5.

The punch plate 39 is carried by posts 42 secured as by means of screw bolts to said plate, said posts projecting loosely into the die block 35 and having stops to limit their upward movement under pressure of springs 44 upon which the punch plate 39 is seated it being understood that said posts are loose for sliding movement only and that they are nicely fitted within their sockets to obviate any lateral movement. The plate 39 is loosely connected with the punch head as by means of hooks 45 in a manner common to machines of this class.

A spring pressed blank retainer is located in a recess in the plate 39, its lower end being forced by said spring into contact with the blank 40 to retain said blank against the die block 35 when the end of the strip 17 is being pushed into the housing to overlie said blank. In this movement of the end of the strip it first encounters the rounded end of a guide 47 located at the edge of the hole through which the punch 38 passes and as shown in Figure 5 of the drawings, the end of the strip at this time having passed the end of the blank underneath it, and in its further movement the end of said strip encounters the end of the retainer 46 and pushes it upward sufficiently to permit the end of the strip to pass.

As hereinbefore explained the housing 34 is provided with a hole for the passage of the punch 38, this hole 48 being located at some distance from openings 49 in the housing for passage of stamping punches 50 secured to and projecting from the punch plate 39, there being as many of these stamping punches as may be desired, for marking, names, trade-marks &c., on the end of the strip 17 and that is effected at the same time the end of the strip is cut off to form the blank 40.

After said blanks have been created they are transferred to forming mechanism that comprises two transfer pushers 51 secured to and projecting from the ends of transfer slides 52 longitudinally movable in transfer housings 53 secured to projecting portions of the die block 35, and as shown in Figure 3 of the drawings. The slides are connected by links 54 with branches 55 of a transfer lever that comprises a shaft 56 journaled in bearings in brackets 57 secured to the back of the bed 36, and as shown in Figure 6 of the drawings, said lever further comprising an actuating arm 58 secured to the shaft 56 and projecting for operation by a transferring cam 59 secured to the cam shaft 24. The transfer pushers project through holes in the back of the housing 34, said housing being open at its opposite or front side for the passage of blanks from within the housing by the operation of said pushers.

From the foregoing description it will have been noticed that the blanks underlie the end of the strip at the time the blanks are removed from the housing in the manner above described, the pushers 51 moving said blanks from beneath the end of the strip, and from this position said blanks pass over the tops of spring seated supporting pins 60 and against positioning fingers 61 projecting from the ends of spring seated positioning and supporting pins 62, said pins being located in recesses in the block 35, and as shown in Figures 7 and 8 of the drawings. When supported by the pins 60 and 62 the blanks underlie a forming die 63 secured to the punch

plate 39 and that acts in cooperation with a forming punch 64 secured to and projecting from the upper side of the die block 35. A spring seated stripper 65 movably mounted

5 in the die 63 may be employed if desired for insuring removal of the blanks from the die.

After a blank has been formed by means of the die and punch 63 and 64, the ejecting pusher 28, that is of a shape in cross section

10 similar to that of a formed blank and that fits over the end of the punch 64, as hereinbefore described, pushes the formed blank lengthwise along the forming punch and off the end thereof for delivery to any desired

15 position.

In the operation of the mechanism herein described, a blank having just been formed on the punch 64, the punch head 13 is raised, thus permitting the punch plate 39 to be

20 lifted by the springs 44. The cam 23 now actuates the lever 21 to move the gripper 18 and the ejecting pusher 28 simultaneously

25 thereby feeding the end of the strip 17 into the housing 34 and ejecting a formed blank from the punch 64. When the end of the strip enters the housing it passes over a cut off blank therein, as hereinbefore described.

At about the time that the end of the strip reaches its innermost position the transfer-

30 ring pushers 51 are operated by the cam 59 to remove the cut off blank from the housing and transfer it to the forming punch 64, and at about this same time the gripper 18 is moved backwardly, during which movement

35 the end of the strip 17 is held by the retaining pawl 30. After the pushers 51 complete their transferring movement they are at once retracted and the punch head is then moved downwardly operating the punch plate 39

40 and thereby simultaneously cutting off the end of the strip 17 to create the blank 40, stamping the end of said strip and also forming a blank previously deposited on the punch 64, the feeding of the strip and the

45 transfer of the blank taking place between each downward movement of the punch head and the three operations of cutting off, stamping and forming taking place at each downward movement of the punch head.

50 In accordance with the provisions of the patent statutes I have described the principles of operation of my invention, together with the device which I now consider to represent the best embodiment thereof; but

55 I desire to have it understood that the device shown is only illustrative and that the invention may be carried out by other means and applied to uses other than those above set out.

I claim:—

60 1. A machine comprising means for moving a blank in one direction to a position for operation thereon, means for moving said blank in a transverse direction to another and different position for operation thereon, a

65 single means carrying work performing ele-

ments for performing successive operations upon said blank in said different positions, and means for further moving the blank in its initial direction of movement.

2. A machine comprising means for moving a blank in one direction to a position for operation thereon, means for moving said blank in a different direction to another and different position for operation thereon, a reciprocating member for performing successive operations upon said blank in said different positions at each successive reciprocating movement of said member, and means for further moving the blank in its initial direction of movement.

70 3. A machine comprising means for moving a blank to a position overlying and resting upon another blank, means for moving the other blank from underneath the first blank to another position, and means for simultaneously performing an operation upon each of said blanks.

75 4. A machine including means for moving a blank in one direction to a station occupied by another blank, means for moving said other blank in a transverse direction to another position, and a single member carrying work performing elements for simultaneously performing an operation upon each of said blanks, and means for removing said

80 blanks in the initial direction of movement.

5. A machine comprising means for moving a blank in one direction to a position overlying and resting upon another blank, means for moving the other blank in a transverse direction from underneath the first blank to another position, and means for simultaneously performing an operation upon each of said blanks.

90 100 6. A machine comprising means for moving a blank to a position overlying and resting upon another blank, means for imparting movement to the under blank simultaneously with the movement of the first mentioned blank to remove it from underneath the first blank and to another position, and a single means for simultaneously performing an operation upon each of said blanks.

105 110 7. A machine comprising means for feeding the end portion of a strip of material to one station occupied by a blank previously cut from said strip, means for imparting movement to said blank simultaneously with the movement of the strip to another position, and means for cutting off the end of said strip.

115 120 125 8. A machine comprising means for feeding the end portion of a strip of material in one direction to a position overlying a blank previously cut from said strip, means for next moving said blank in a transverse direction from underneath the end of the strip to a different position, and means for next severing the end of said strip to form a blank

130

and, simultaneously therewith, for performing an operation upon each of said blanks.

9. A machine comprising means for feeding the end portion of a strip of material to one station occupied by a blank previously cut from said strip, means for imparting movement to said blank simultaneously with the movement of the strip to another position, and means for simultaneously cutting off the end of said strip and for performing an operation on said blank.

10. A machine comprising means for feeding the end portion of a strip of material to one station occupied by a blank previously cut from said strip, means for moving said blank to another position, and means for simultaneously cutting off the end of said strip for performing an operation on said cut off end and for performing an operation on said blank.

11. A machine comprising means for moving a blank to a station occupied by a second blank, one of said blanks overlying the other, means for moving said second blank from said station, while the first blank remains and means for performing an operation upon one of said blanks in said station.

12. A machine affording two stations to receive blanks for operation thereon, comprising means for positioning two blanks at one of said stations, means for moving one of said blanks separately from one of said stations, and means for simultaneously performing an operation on both of said blanks when located one at each of said stations.

13. A machine comprising a head having a reciprocating movement, means for feeding a relatively long blank longitudinally to a position underneath said head and then for feeding another relatively long blank laterally to a second position underneath said head and after each reciprocating movement thereof, and means for causing said head to effect an operation upon a plurality of blanks at each reciprocating movement of the head and in said different positions.

14. A machine comprising a head having a reciprocating movement, means for feeding the end of a strip in one direction to a position underneath said head and then for feeding a blank previously cut from said strip in a transverse direction to a second position underneath said head, and between succeeding reciprocating movements of said head, and means for causing said head to effect an operation upon a plurality of blanks and to sever the end portion of said strip at each reciprocating movement of the head.

15. A machine affording stations at which operations are performed upon blanks, comprising means for moving blanks from one to another of said stations, and a single pusher carrying device operable to simultaneously feed a blank to the machine and to move

a blank from one of said last mentioned stations.

16. A machine affording a plurality of stations at which different work is performed, comprising means for simultaneously moving blanks in the same direction to the first station and from the last station, means for moving blanks in a transverse direction from one to the other of said stations, and means for performing operations upon said blanks at each of said stations.

17. A machine affording a plurality of stations at which different work is performed, comprising means for simultaneously moving blanks in the same direction to the first station and from the last station, means for then moving a blank from one to another of said stations, and means for then operating upon a blank at each of said stations.

18. A machine affording a plurality of stations at which different work is performed for receiving blanks, comprising means for moving blanks in one direction from one to another of said stations, and means for simultaneously feeding the end of a strip of material to one of said stations, for removing a formed blank from another of said stations, and a reciprocating head having means for simultaneously cutting off the end of said strip, for stamping a blank at one of said stations and for forming a blank into trough shape at another of said stations.

19. A machine affording a plurality of stations at which different work is performed for receiving blanks, comprising means for moving blanks in one direction from one to another of said stations, a movably mounted member for simultaneously feeding the end of a strip to one of said stations and for removing a formed blank from another of said stations, and a reciprocating head having means for simultaneously cutting off the end of said strip, for stamping a blank at one of said stations and for forming a blank into trough shape at another of said stations.

20. A machine including means for holding two blanks in work performing positions, a single blank pushing device for simultaneously moving a new blank into the machine above one of the two blanks and the other of the two blanks out of the machine, and an additional blank pushing device for moving the blank underlying the new one into the work performing position formerly occupied by the other of said first two blanks.

21. A machine including means for holding a blank of elongated formation in a work performing position, means for moving an additional similar blank longitudinally into the machine, and means for guiding the additional blank into a position above and in contact with the first mentioned blank.

22. A machine including means for holding a blank of elongated formation in a work performing position, means for moving an

additional similar blank longitudinal into the machine, means for guiding the additional blank into a position above the first mentioned blank, and means for moving the first mentioned blank transversely out from under the additional blank.

23. A machine including relatively movable members, cutting elements carried by said members, a housing associated with one of said members, means for moving a strip into said housing to have a blank cut therefrom, means for guiding the end of the strip into a position above a previously cut blank, and means for removing said previously cut blank from beneath the end of the strip prior to the cutting of a new blank.

24. A machine including relatively movable members, cutting elements carried by said members, a housing associated with one of said members, means for moving a strip longitudinally into said housing to have a blank cut therefrom, means for guiding the end of the strip into a position above a previously cut blank, and means for removing said previously cut blank transversely from beneath the end of the strip prior to the cutting of a new blank.

25. A machine including relatively movable members, cutting elements carried by said members, a housing associated with one of said members, means for moving a strip longitudinally into said housing to have a blank cut therefrom, means carried by said members for guiding the end of the strip into a position above a previously cut blank, and means for removing said previously cut blank from beneath the end of the strip prior to the cutting of a new blank.

26. A machine including relatively movable members, cutting elements carried by said members, a housing associated with one of said members, means for moving a strip longitudinally into said housing to have a blank cut therefrom, spring pressed plungers for guiding the end of the strip into a position above a previously cut blank, and means for removing said previously cut blank from beneath the end of the strip prior to the cutting of a new blank.

27. A machine including relatively movable members, cutting elements carried by said members, a housing associated with one of said members, means for moving a strip longitudinally into said housing to have a blank cut therefrom, oppositely acting spring pressed plungers carried by said members for guiding the end of the strip into a position above a previously cut blank, and means for removing said previously cut blank from beneath the end of the strip prior to the cutting of a new blank.

28. A machine including relatively movable members, cutting elements carried by said members, a housing associated with one of said members, means for moving a strip

longitudinally into said housing to have a blank cut therefrom, oppositely acting spring pressed plungers carried by said members for guiding the end of the strip into a position above a previously cut blank, and means for removing said previously cut blank from beneath the end of the strip prior to the cutting of a new blank, one of said plungers acting to position a cut blank so that the end of the strip may be guided into the position above said blank.
